UNITED STATES PATENT OFFICE.

WILLIAM H. BROWN AND WILLIAM H. BELL, OF NEW ORLEANS, LA.

DREDGING-MACHINE.

SPECIFICATION forming part of Letters Patent No. 250,877, dated December 13, 1881.

Application filed October 20, 1881. (No model.)

To all whom it may concern:

Be it known that we, WILLIAM H. BROWN and WILLIAM H. BELL, residents of the city of New Orleans, parish of Orleans, and State 5 of Louisiana, have invented a certain new and useful Improvement in Dredging-Machines; and we do hereby declare the following to be a full, clear, and correct description of the same, reference being had to the annexed drawings, 10 making a part of this specification.

This invention provides for the removal of sand-bars and other obstructions in rivers and streams; and it consists in a means for harrowing or loosening the surface of the obstruction, 15 and in driving the loosened material to the sides of the channel.

The nature of our invention will be more readily understood by referring to the accompanying drawings, whereon—

20 Figure 1 represents a side view of a portion of a boat provided with our improved apparatus, and Fig. 2 a perspective view of our revolving harrow and interior blades or propellers.

Our harrow is composed of a number of 25 wheels, A, to the peripheries of which are bolted or otherwise secured longitudinal strips b, having cutting-edges, as at c, and upon their outer surfaces points or cutters d. The wheels A are loosely fitted on a shaft, E, and the outer 30 wheels have hubs or sleeves extending outward, so as to have keyed or otherwise fitted thereupon driving-wheels, as at f, by which means the harrow can be revolved independent of the shaft upon which it is fitted and the propeller-blades have a more rapid speed to stir, 35 mingle, and discharge the material on opposite sides at right angles to the current.

The blades F, similar to those of an ordinary propeller, are secured to the shaft E in such 40 a manner as to permit of their being reversed, (should the nature of the work so require,) and thus drive the loosened material to either or both sides of the channel.

The journals of the rotary harrow and inner 45 shaft operate in outriggers G, the opposite ends of which are fitted on a shaft, h, that is provided with cranks i, so that the same may be operated by a steam-engine or other motive power. Upon the outer ends of the aforesaid 50 shaft are fitted sprocket-wheels k, which,

through endless sprocket-chains l and sprocket-wheels f, afford means for operating the harrow. A second set of wheels, n, are keyed or otherwise secured to the shaft h, for the purpose of transmitting motion to the shaft E and 5 its propelling-blades.

On the deck of the boat is erected a frame or derrick, from the upper portion of which connection is made through block and tackle with the outer end of the outriggers, so as to provide for a proper adjustment of the operating mechanism, as well as for raising the same for repair, or during such time as the boat is changing location.

For operating in heavy clay it is deemed 65 best to rigidly secure the harrow to the shaft, and to connect the outer extremities of the propeller-blades with the longitudinal bars of the harrow, so that the harrow and propellers will revolve together, inasmuch as this mode of 70 construction will render the whole much stiffer, and consequently less liable to break.

Our improved mode of constructing the harrow with internal blades not only affords protection to the said blades, but insures their 75 driving the loosened material out through the ends of the harrow entirely clear of the channel, and thereby tending to build up embankments on the sides of the same.

From the foregoing description and reference to the drawings it will be observed that the revolving harrow loosens the material forming the bar, and the propeller-blades in connection therewith cause the loosened material held in suspension to be driven sidewise 85 by the artificial current produced by the revolving motion of the propellers, and carried off on each side of the machine, thereby removing the sand-bar from the channel without prolonging the bar.

Having described our invention, what we 90 claim as new, and desire to secure by Letters Patent, is—

1. The combination, with a revolving harrow, of a series of propeller-blades arranged 95 within the said revolving harrow, substantially as described.

2. The combination, with a revolving harrow, of a series of propeller-blades mounted on a shaft, and revolving concentrically with 100

the harrow, and having a different velocity therefrom, substantially as and for the purpose set forth.

3. In a means for removing sand-bars and deepening channels, the combination, with the revolving harrow having the cutters and the series of propeller-blades arranged within the harrow, of the sprocket wheels and chains for communicating motions of different speed to the revolving harrow and propeller-blades, substantially as set forth.

4. In a revolving harrow, the longitudinal strips *b*, having the cutting-edges *c* and cutters *d*, substantially as described.

In testimony whereof we hereunto sign our names.

W. H. BROWN.
W. H. BELL.

In presence of—
P. J. FINNEY,
J. C. HUBBELL.
